ADDRESS PLATE

Warren B. Detwiler, North Hills, Pa., assignor to
 Curtis Publishing Company, Philadelphia, Pa.,
 a corporation of Pennsylvania

Application August 8, 1932, Serial No. 627,856

1 Claim. (Cl. 101—369)

Address plates are inked by ribbons or ink pads and they are used in large numbers in machines for printing the names and addresses appearing on the mailing lists of magazine publishers and other business houses. The names and addresses are embossed on the plates by means of cooperating types and dies, and are subject to change. Large numbers of the plates have to be sorted and filed by hand, and for this purpose the legends 10 on them have to be read from the sunken side and it is necessary to store the plates in large quantities.

So far as I am aware such plates, with the exception of so-called stencil cards, which are of thin paper framed in cardboard and are not really plates, have been made of metal and embossed and in some cases provided with folded or rolled side edges.

Generally stated, the present invention comprises the substitution of so-called "fiber", a sheet product of indurated paper-like material made from cotton, in place of metal in the manufacture of address plates. This fiber is chemically treated and hardened fiber. It consists of cellulose made from cotton fiber paper and treated chemically with zinc chloride, which is the laminating agent. The result is known as chemically treated and hardened fiber. The trade name is vulcanized fiber. In view of the new mode of construction, the development of new properties, the increased efficiency, and the saving in cost of installation and operation, thereby effected; and in view of the fact that the excellence of the substituted material, "fiber" could 30 not have been ascertained beforehand without experimentation and trial, and because practice shows the superiority to consist in greater cheapness, durability and efficient action, new results are obtained.

40 In the drawing

Figure 1 illustrates an address plate embodying features of the invention, but the invention itself is of such character that it is incapable of satisfactory illustration.

45 Fig. 2 is a transverse section of Fig. 1.

Fig. 3 illustrates a flat plate, and

Fig. 4 is a transverse section of Fig. 3.

Practice has demonstrated that addresses embossed on fiber plates can be easily, quickly and accurately read, which facilitates and cheapens the operation of sorting and filing them and makes that operation more efficient. This is due to the fact that the sunken letters and figures, readable from left to right on the non-printing 50 side of the plate, present a dark or even black

color appearance in sharp contrast with the face of the fiber plate, which may be grayish white, or reddish or of other color. This excellence of fiber for address plates was not known or appreciated beforehand and was demonstrated by 5 practice. After demonstration it can be accounted for by some rather occult physical structure or property of the face of the "fiber" which, in the light and however viewed, gives the dark color effect to the sunken characters. In this 10 connection it may be called to mind that the reflecting surface of a metal address plate makes the sunken characters difficult to read, except in a certain light, so that the sorters have to put the plates in that position in order to read 15 them, which requires time. Likewise the letters or characters can be blocked out from a fiber address plate and re-embossed without impairing legibility, and this is not true of metal address plates. This quality or excellence of fiber address 20 plates could not have been foretold and it was ascertained in practice, contrary to expectation. In blocking out a fiber address plate it does not spread, whereas a metal plate does.

A fiber address plate is possessed of increased 25 efficiency, a saving in cost of installation and operation, and embodies a new construction and properties, and some of these will be referred to. Fiber address plates are roughly of only one-third of the weight of metal plates which facilitates and cheapens their storage when not in use in an addressing machine. The impression from a fiber plate is surprisingly sharper than from a metal plate, although the embossing machine requires less pressure. Fiber is of course 30 cheaper per plate than metal and it is better as herein pointed out. Fiber plates do not bend in the embossing machine as metal plates tend to do, and if, when out of the embossing machine, they are bent, they can be restored for use. This 35 is an unexpected property, which metal does not possess, and it is probably due to the physical constitution of the body of the fiber. The edges of a fiber plate are blunt and will not cut the hands of the sorters, whereas the edges of metal plates are so sharp that the side edges of certain types are rolled to avoid injury to the hand of the sorters, but the end edges cut the hands of the sorters and often produce metal poisoning. If it is desired to stiffen plates and to space them 40 in filing they may be indented as indicated at 1 in the drawing. The properties last referred to give rise to a new construction, and without trial and practice they were not obvious.

45 Embossable fiber lends itself to production in 55

different colors, which is not true of metal, and this is useful in quickly distinguishing the address plates which appertain to one of several mailing lists. If moisture in the atmosphere requires, the fiber address plates may be dipped in oil.

It has been found that in the addressing of a list, label, or envelope, there is less pressure required in the printing machine when fiber is used, in comparison with metal, consequently ribbon or ink pads can contain less ink and likewise there will be less wear and tear on ribbons and pads. Also, in addressing machines, break-

age of metal plates often occurs, and it has been found that if a fiber plate breaks in the printing machine, it is less destructive to the machinery than metal because of the fact that it will shred or tear rather than bend and block the machinery.

I claim:

An address plate made of fiber and having characters sunk therein which impart a black color effect by contrast with the color of the face of the plate.

WARREN B. DETWILER.
